UNITED STATES PATENT OFFICE.

FRANK M. CASTLEMAN, OF ROTHERHAM, ENGLAND, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA.

RAISING AND LOWERING COAL CHUTES.

Application filed May 22, 1922. Serial No. 562,927.

To all whom it may concern:

Be it known that I, FRANK MASTERS CASTLEMAN, a subject of the King of Great Britain, residing at Rotherham, in the 5 county of Yorkshire, England, have invented certain new and useful Improvements in Raising and Lowering Coal Chutes, of which the following is a specification.

This invention relates to coal chutes and 10 the like, and has for its object to provide improved arrangements for effecting the raising and lowering of the chute to discharge the coal or other contents into a tub, truck, or other receptacle.

15 The invention is illustrated in the accompanying drawings, of which—

Figure 1 is a view in side elevation partly 20 diagrammatic of a coal chute provided with raising and lowering mechanism arranged in accordance with one form of the invention,

Figure 2 being a view thereof in end elevation.

Referring now to the drawings it will be 25 seen that the chute 1 consists of a lattice girder structure pivotally mounted at one end thereof as indicated at 2 on a suitable framework or staging 3 arranged above the track rails 4 for the tubs or trucks 5 to be 30 filled from the chute, and comprises a moving conveyer belt 6 by means of which the coal is arranged to be conveyed from the screens to the chute. The conveyer belt 6 is arranged to be driven by means of an 35 electric motor through any suitable mechanism not shown.

The end 7 of the chute at which the coal is discharged is arranged to be moved to its lowered position in which it enters the tub 40 or truck 5 to be filled by means of a ram or plunger 8 device operated by fluid under pressure, the supply of which is controlled by means of an electro-magnetically actuated valve 9, the ram or plunger 10 of the 45 device being arranged at a suitable level vertically above the discharge end 7 of the chute 1, the casing or cylinder 11 of the ram or plunger 10 being pivotally mounted as indicated at 12 so as to enable the ram 50 10 which is pivotally connected at 13 to the discharge end 7 of the chute, to follow the arc of movement of the chute.

The chute 1 is arranged to be moved to its upper or raised position in which it is

above and clear of the tub or truck 5 by 55 means of a pair of ropes 14 one end of each of which is connected at 15 to suitable points in the chute 1, the other end of each rope 14 passing over a pulley 16 mounted upon a horizontal shaft 17 at substantially the level of the pivot 12 of the ram cylinder 11 and provided with a suitable balance or counter-weight 18. The horizontal shaft 17 above referred to is also provided with a brake drum 19 rigidly secured to the shaft 17 as shown in Figure 1, the drum 19 being provided with a brake block 20 adapted to be moved into engagement with the drum 19 so as to prevent or retard the rotation of the latter by means 65 of a suitable weight 21, which is secured to one end of a lever 22 the opposite end of which is pivotally mounted as indicated at 23. The brake block 20 is arranged to be released from the drum 19 by means of a device 24 actuated by fluid under pressure and controlled by an electro-magnetically actuated brake valve 25.

The balance or counter-weight 18 is preferably equal to the combined weight of the 80 chute 1 and of the coal carried by the conveyer belt 6 forming part of the chute, so that when the conveyer belt 6 is empty the chute 1 tends to be raised by the action of the balance or counter-weight 18 to its 85 upper position, whereas when the conveyer belt 6 is carrying coal the weight of the loaded chute is approximately counter-balanced.

The circuits of the electro-magnetically actuated valve 9 controlling the supply of 90 fluid under pressure to the ram device 8, hereinafter termed the ram valve, and of the valve 25 controlling the supply of fluid under pressure for releasing the brakes, hereinafter termed the brake valve, are arranged to be controlled by means of an operator's switch 26 having two operative positions indicated at R, L for raising and lowering the chute respectively, and an intermediate or "off" position O.

When the operator's switch is set to the lowering position L a circuit is completed from the positive terminal of a battery 27 or other suitable source of electric current through conductor 28, the switch 26, conductor 29, the energizing winding of the ram valve 9, conductor 30, the energizing winding of the brake valve 25, and conductor

31 to the negative terminal of the battery 27. As a result, fluid under pressure is supplied both to the ram casing 11 and to the device 24 for releasing the brake block 20 5 from the drum 19. The ram or plunger 10 is thus moved downwards carrying with it the discharge end 7 of the chute 1 so that the coal carried by the chute is discharged into the tub or truck 5 below, the brake block 10 20, being released from the drum 19 during this movement.

When, on the other hand, the operator's switch 26 is subsequently moved to the raising position R a circuit is completed from 15 the positive terminal of the battery 27, conductor 28, switch 26, conductor 32, which includes a suitable resistance 33, conductor 30, the energizing winding of the brake valve 25, conductor 31 to the negative 20 terminal of the battery 27. As a result, the brake block 20 being released from the drum 19 the chute 1 rises under the action of the balance or counter-weight 18 to its uppermost position. By moving the operator's switch to the "off" position O during either of these operations the coal chute 1 can evidently be held stationary in any 25 desired position intermediate its raised and lowered positions.

30 It will be understood that when the actuating magnets of the ram or brake valves 9, 25, are de-energized these valves permit the release of fluid from the ram casing 11 or from the casing of the device 35 24 controlling the brake, so that these devices are inoperative.

In order to prevent any possibility of a 40 tub or truck passing under and engaging with the coal chute 1 when in its lowered position a safety switch 34 may be provided adapted to be automatically operated by an approaching tub or truck and to complete an independent circuit from the battery 27 by way of conductors 28, 35, 36, through the 45 energizing winding of the brake valve 25, so as to permit in these circumstances the brake block 20 to be released from the drum 19 thus causing the chute 1 to rise to its upper position under the action of the 50 balance or counter-weight 18.

Furthermore, in order to prevent the coal chute 1 from being supplied with coal by means of the conveyer belt 6 when the chute 1 is in its raised position a second 55 switch 37 actuated by the chute 1 when in this position may be arranged to open the circuit of the electric motor driving the conveyer belt 6 so that unless the chute be in its lowered position the belt 6 is not 60 driven to supply coal to the chute.

The constructional arrangements above described may evidently be modified in various respects without exceeding the scope of the invention.

65 Having now particularly described and

ascertained the nature of my said invention and in what manner the same is to be performed, I declare that what I claim is:—

1. In combination, a movable chute, a counterweight for biasing said chute to a given position, a fluid pressure device for moving said chute from said given position, and an electro-magnetically operated valve for controlling the supply of fluid pressure to said device. 75

2. In combination, a movable counter-weighted chute, a fluid pressure device for operating said chute, braking mechanism for said chute, a second fluid pressure device for operating said braking mechanism, and electro-magnetic means for controlling said fluid pressure devices. 80

3. In combination, a movable counter-weighted chute, normally effective braking apparatus, a fluid pressure device for rendering such apparatus ineffective, and manually operable means for controlling said device. 85

4. In combination, a movable counter-weighted chute, normally effective braking apparatus, a fluid pressure device for rendering such apparatus ineffective, and electro-magnetic means for controlling said device. 90

5. In combination, a movable counter-weighted chute, normally effective braking apparatus, a fluid pressure device for rendering such apparatus ineffective, electro-magnetic means for controlling said device, and manually operable means for controlling said electro-magnetic means. 95 100

6. In combination, a pivoted chute, a pulley, a counterweight, a flexible member passing over said device for connecting said counterweight with said chute, a friction brake normally biased into a position wherein movement of said pulley is prevented, a fluid pressure device adapted to move said brake mechanism against such bias into a position wherein motion of said pulley is permitted, and electro-magnetic means for controlling said device. 105 110

7. In combination, a pivoted chute normally biased to an upper position, a fluid pressure device for at times moving said chute to its lower position, a braking mechanism for holding said chute in any given position, a second fluid pressure device for controlling said brake and manually operable means for controlling said fluid pressure devices. 115 120

8. In combination, a pivoted chute for discharging material to a movable receiver and biased to an upper position, means for at times moving said chute to a lower position, braking mechanism for holding said chute in any given position, and means for controlling said braking mechanism in accordance with movement of said receiver. 125

9. In combination, a pivoted chute for dis-

charging material to a movable receiver and biased to an upper position, means for at times moving said chute to a lower position, braking mechanism for holding said chute in any given position, and means operative when such receiver approaches said chute, to release said braking mechanism.

10. In combination, a pivoted chute for discharging material to a movable receiver and biased to an upper position, means for at times moving said chute to a lower position, braking mechanism for holding said chute in any given position, a contact adapted to be operated when such receiver approaches said chute, and electro-magnetic means controlled by said contact for releasing said brake.

11. In combination, a pivoted chute for discharging material to a movable receiver and biased to an upper position, and comprising a movable conveyor belt, means for at times moving said chute to a lower position, and means for operating said conveyor belt only when said chute is in its lower position.

12. In combination, a pivoted chute biased to one position, a fluid pressure device adapted when supplied with fluid pressure to move said chute to a different position, a first electro-magnetic valve adapted when energized to supply fluid pressure to said first fluid pressure device, a braking mechanism normally effective to hold said chute in any given position, a second fluid pressure device adapted when supplied with fluid pressure to release said braking mechanism, a second electro-magnetic valve adapted when energized to supply fluid pressure to said second fluid pressure device, a manually operable switch comprising two contacts either one of which may be closed at will; an electrical circuit including a source of energy, said first electro-magnetic valve, said second electromotive valve, and one of said contacts; and a second electrical circuit including a source of energy, said second electro-magnetic valve and the remaining said contact.

In testimony whereof I affix my signature
FRANK M. CASTLEMAN.
